ABSTRACT: The centrifugal rotor is provided with a first valve movable hydraulically to open and close the peripheral outlet through which centrifugally separated sludge is discharged from the rotor, the rotor having another outlet for the operating liquid by which the valve is actuated. A second valve is hydraulically actuated to open this operating liquid outlet and is urged by a biasing means in the direction for closing the latter outlet, the rotor also having a chamber so located and dimensioned that a liquid substantially filling this chamber acts to urge the second valve in its closing direction with a force in addition to the force of said biasing means.

SLUDGE CENTRIFUGE

THE DISCLOSURE

This invention relates to sludge centrifuges of the type in which separated sludge is discharged from the centrifugal rotor intermittently under control of a first valve actuated hydraulically by an operating liquid for which the rotor has a separate outlet adapted to be opened by hydraulic actuation of a second valve, the rotor having biasing means for urging the second valve in the direction for closing the operating liquid outlet.

A centrifuge of this type is disclosed in Swedish Pat. No. 125,439. The closing of the second valve of this centrifuge is effected by means of biasing springs after the main portion of the operating liquid has discharged through the outlet. During the later part of this discharge period there is a stage of balance between the opposing forces acting to open and to close the second valve, and this stage is passed relatively slowly. Thus, the closing of the second valve will take place with an undesired delay.

According to the present invention, a more rapid closing of the second valve is effected by subjecting it to a hydraulic actuation in the closing direction. More particularly, at the moment when the closing is to be effected, a liquid is supplied to a chamber so located in the rotor and having such a radial extension that liquid substantially filling the chamber is operable to give the second valve an additional actuation in the closing direction.

Between the sludge discharges the liquid in the chamber is to be drawn off. Even if this can take place by leakage, it is desirable to provide the chamber with a throttled outlet, preferably from its radially outer part.

According to a preferred embodiment of the invention, the chamber is located in the discharge path of the operating liquid which actuates the first valve. Due to the fact that the chamber is filled with liquid in this way, a closing hydraulic actuation of the second valve is obtained very rapidly and at a correct point of time.

According to the invention, it is possible to obtain either a total or a partial discharge of the content of the rotor's separating chamber. The total discharge is desired when sludge deposits caked together are to be removed from the sludge space, and the partial discharge is desired when only deposited sludge and not separating liquid is to be discharged. The partial discharge allows uninterrupted supply of separating liquid to the centrifuge, without liquid losses occurring.

The total discharge can be obtained by giving the chamber such a volume that it can receive all operating liquid flowing from the outlet of the first valve, without the second valve being actuated in its closing direction. The closing of the second valve is obtained automatically when the liquid acting to open this valve is drained from the space where it effects the opening force, but such closing of the second valve can be accelerated by supplying additional operating liquid to the chamber through a separate channel at the correct moment.

A desired partial discharge can be obtained by supplying a limited quantity or a limited flow of operating liquid, corresponding to this partial discharge, to the chamber through the separate channel. In this way, a controlled prefilling of the chamber is effected whereby the outlet from the first valve is closed before the total content of the separating space has been discharged.

According to a feature of the present invention which facilitates attaining a desired degree of partial discharge, the chamber has a starting or minimum liquid level provided by an overflow outlet with limited outlet area and which is located, calculated radially, inside the outer part of the chamber; and the additional operating liquid, corresponding to the desired degree of partial discharge, is supplied to and builds up from this starting level. In order to make it possible to adapt this overflow outlet to different operational situations, it is made adjustable in the radial direction, preferably in such a way that

it can be screwed radially inward or outward by actuation from the outside of the centrifuge rotor.

If the centrifuge is used only for partial discharge, rings of solid material (metal or the like) can be placed in the chamber 5 the volume of these rings corresponding to the prefilling volume which, as noted above, is determined by the position of the overflow outlet.

The invention is described more in detail below, reference being had to the accompanying drawing in which FIG. 1 is an axial sectional view of the main part of the left-hand half of an embodiment of the new centrifuge, and FIG. 2 is a similar view showing a fragment of a modified embodiment. In the two figures, corresponding details have the same reference numerals.

In FIG. 1, a rotor body 1 is provided with a cover 2 secured by a locking ring 3. A set of conical discs 5 is provided in the separating space 4, and the liquid to be separated is supplied from above through a distributor 6. The centrifuge is mounted on and driven by a spindle 7. The rotor wall has sludge outlet openings 8 which are closed by a piston valve 9 when it is actuated upwardly by means of operating liquid supplied through a stationary pipe 10 to a space 11 at the underside of the valve 9. A ring valve 13 is pressed upward by springs spaced around the rotor axis and of which one is shown at 12. In the upper position of valve 13, its cushions 14 (made of nylon, for example) keep outlets 15 from the space 11 closed. A space 16 above the valve 13 is drained through throttled outlets 17. An annular chamber 18 with throttled outlets 19 is provided in 30 the rotor wall at the underside of the valve 13. An annular chamber 20 with three different overflow outlets 21, 22 and 23 is provided in the central portion of the rotor bottom. An additional stationary pipe 24 for the supply of operating liquid opens into the chamber 20, and from the chamber 20 a channel 25 leads to the space above the valve 13 and a channel 26 leads to the chamber 18. A slot between the ring valve 13 and an annular ridge 18b on the rotor bottom is designated by 18a. The space 16 communicates with the chamber 18 through channels 27 which pass through the ring valve 13 and the openings of which at the upper side of the ring valve are located between the cushions 14.

In FIG. 2, the chamber 18 is provided with an overflow outlet 28 in the form of a pipe piece, which can be screwed radially inward or outward.

In the operation of the FIG. 1 centrifuge, after a sludge discharge through the openings 8, the ring valve 13 is pressed to closing position by the springs 12, the cushions 14 closing the outlets 15. Liquid is supplied in such a quantity through the pipe 10 that the space 11 is filled, the valve 9 being closed. Separating liquid again fills the separating space 4. When sludge is to be discharged, an additional quantity of liquid is supplied through the pipe 10, so that it flows over the overflow outlet 21 and reaches the space 16 via the channel 25. In this space the liquid exerts such a pressure against the upper side of the ring valve 13 that the valve is pressed downward against the action of the springs 12. The liquid contained in the space 11 flows (together with the smaller quantity of liquid supplied through the channel 25) downward into the chamber 18 via the channels 27. The latter chamber has such a large volume that it can receive the whole quantity of liquid passed into the chamber, without the liquid level in the chamber 18 being displaced so far inward that the pressure generated by the liquid causes closing of the valve 13. The latter, however, is closed by the springs 12 when the liquid in the space 16 has been drained through the outlets 17. In this case, there occurs a total discharge of the content of the separating space. On the other hand, if a partial discharge of the content of the separating space 4 is desired, a limited quantity or a limited flow of liquid is supplied through the pipe 24, when a sludge discharge is to be effected. In this way, a certain liquid level in the chamber 18 is provided in advance, whereby the liquid arriving from the space 11 will displace the liquid level sufficiently inward so that the liquid in the chamber 18 and in the narrow slot 18a will, in cooperation with the springs 12, actuate the

valve 13 so that it closes earlier than in the preceding case. Due to the fact that the slot 18a is narrow, the liquid level moves rapidly inward in this slot. This leads to a rapid increase of the hydraulic pressure against the underside of the valve 13 and to a corresponding rapid closing of the valve. Only a partial discharge of the content of the separating space 4 now takes place. A desired degree of partial discharge can be attained by control of the liquid supply through the pipe 24. After the valve 13 has been closed, the space 18-18a is drained through the outlets 19.

In the embodiment according to FIG. 1, the liquid supply through the pipe 24 can cause the liquid level in the chamber 18 to fluctuate. In order to achieve an improved accuracy, as regards the degree of partial discharge, the arrangement according to FIG. 2 is provided in the chamber 18 with an overflow outlet 28 having a limited cross section in the form of a pipe piece which can be screwed in the radial direction. This means that operating liquid, entering from the pipe 24, fills the chamber 18 only to a level which is determined by the position of the inner opening of the pipe piece 28. Operating liquid, entering with high velocity from the space 11, now fills the chamber 18 from a level (determined by the overflow outlet 28), with the result that the valve 13 is closed after a more exact space of time than is possible in the embodiment according to FIG. 1. The said space of time can, according to the desired degree of partial discharge, be adjusted by screwing the pipe piece 28 inward or outward. Another possibility of attaining a desired degree of partial discharge is to change the volume of the outflow path of the liquid upstream from the chamber 18, for example, by means of insertion bodies (not shown).

I claim:

1. A sludge centrifuge comprising a rotor provided with an outlet for discharge of centrifugally separated sludge, a first

valve movable hydraulically to open and close said sludge outlet, the rotor having an outlet for an operating liquid by which said valve is actuated, a second valve for opening and closing said operating liquid outlet, the second valve being hydraulically actuated to open the operating liquid outlet, means for biasing the second valve in the direction for closing the operating liquid outlet, the rotor also having a chamber so located and dimensioned that a liquid substantially filling said chamber acts to urge the second valve in said closing direction 10 with a force in addition to the force of said biasing means, and means for substantially filling said chamber with a liquid.

2. A centrifuge according to claim 1, in which said chamber is disposed in the path of liquid flowing through said operating liquid outlet.

15 3. A centrifuge according to claim 1, in which said chamber has a throttled outlet.

4. A centrifuge according to claim 1, in which said chamber is disposed in the path of liquid flowing through said operating liquid outlet, and is adapted to receive all of the flow through 20 said operating liquid outlet without said second valve being actuated in its said closing direction.

5. A centrifuge according to claim 1, in which said means for substantially filling said chamber include a separate channel in the rotor for supplying liquid to said chamber.

25 6. A centrifuge according to claim 1, in which said means for substantially filling said chamber include a separate channel in the rotor leading to the chamber, and means for supplying liquid to said separate channel.

7. A centrifuge according to claim 1, in which said chamber 30 has an overflow outlet of limited outlet area and located radially between the rotor axis and the outer part of said chamber.

8. A centrifuge according to claim 7, in which said overflow outlet is adjustable radially.
